AUTOMATIC DRILL POINTER

John A. Einhiple, Kenmore, N. Y., assignor to National Gypsum Company, Buffalo, N. Y., a corporation of Delaware

Application January 27, 1956, Serial No. 561,752

8 Claims. (Cl. 51—92)

This invention relates to an apparatus for sharpening or pointing drills, or more specifically to a novel automatic drill pointer. Although not limited to such use, the invention is directed to an apparatus for rapidly re-sharpening drills for use in drilling perforated acoustical tiles, the manufacture of which tiles requires a very large number of drills maintained sharp and of identical or equal over-all length. The embodiment of the present invention set forth herein is particularly adapted for re-sharpening the drill described and shown in my earlier United States Patent 2,675,841.

Due to the accuracy required in resharpening drills for acoustical tile both in providing a properly formed drilling end, without any burning of metal, and in providing a large plurality of drills all of equal length, it will be apparent that the heretofore largely manual operation has been an expensive and time consuming operation.

It is, therefore, an object of the present invention to provide a novel apparatus which requires only a relatively rapid insertion and locking in of each individual drill prior to the automatic resharpening, individually, of a large plurality of drills, free of burning, all to an identical, selected length.

These and other objects and advantages will appear more fully when considered in connection with the following detailed description of a preferred embodiment of the invention and the accompanying drawings in which:

Fig. 1 is a side view of an automatic drill pointer built in accordance with and embodying the present invention.

Fig. 2 is a front view of the drill holding and advancing portion and the reciprocal drive of the machine of Fig. 1, parts being broken away.

Fig. 3 is a top view of the drill holding portion of Fig. 2.

Fig. 4 is a sectional view through the guide pins taken along line 4—4 of Fig. 3.

Fig. 5 is a sectional view of the drill holding and advancing portion of Fig. 2 taken along line 5—5 of Fig. 3, certain portions being shown in full.

Fig. 6 is an exploded view of the machine chuck of Fig. 5, portions thereof also shown in Fig. 2.

Fig. 7 is a sectional view of the machine stop-start switch.

In the drawings, the reference numeral 20 refers to the complete automatic drill-pointer machine. Briefly, the machine 20 includes, first, a rotary grinding wheel and drive assembly A providing a continually rotating, profiled grinding means for resharpening drills. Machine 20 includes, second, a combination upper-frame and wheel dressing assembly B. Third, a drill receiving and holding assembly C is laterally slidably mounted on the front of frame assembly B. Fourth, a reciprocal drive assembly D causes the lateral reciprocation of assembly C. Assembly C holds and slowly advances a drill to be sharpened by passing contact with the profiled grinding means of assembly A, the passing contact being provided

2
by the reciprocation of assembly C caused by the operation of assembly D.

Referring now to Fig. 1, there is shown the automatic drill pointer machine 20, built in accordance with and embodying the present invention. A table 21 having a fore and aft extending, raised and dovetailed top 22, provides a support for an adjustably movable framework 25, slidably mounted thereon. Framework 25 includes a dovetailed groove 26 in the base complimentary to and 5 slidably mounted upon dovetailed top 22, for adjustable movement of framework 25 fore and aft. A threaded frame positioning bolt 30, having a handwheel 31 at the front end, is rotatably mounted, longitudinally fixed, in framework 25, and extends into and is threadedly engaged in threaded hole 32 in table 21. Thus, rotation of handwheel 31 and bolt 30 causes framework 25 to slide fore or aft relative to table 21, such action being for repositioning the assemblies B and C of the machine relative to assembly A for the redressing of the grinding 10 wheel and the subsequent grinding operation following redressing, to be discussed further below.

Mounted behind table 21 is a grinding-wheel motor 35 with a shaft 36 having a pulley 37. Belt 38, on pulley 37, is disposed and extends upward between the table and 20 motor 35, and is mounted also on a pulley 40 which is on grinding shaft 41. Grinding shaft 41 is rotatably mounted in bearings 42 fixed on and above table top 22. Pulley 40 is fixed at the rear end of shaft 41 and a hollow, cylindrical, grinding wheel 45 is fixed at the forward end of shaft 41.

As will be seen in Fig. 1, grinding wheel 45 is rotatably disposed within the confines of framework 25, and a forward bearing 42 is shown disposed partially therewithin. Grinding wheel 45, bearings 42 and shaft 41 are 25 stationary relative to table 21, excluding rotation, whereas framework 25 is slidable fore and aft, relative to table 21, and thus also relative to grinding wheel 45.

Briefly, framework 25 includes two grinding wheel dressing units, namely an upper, angular, dressing unit 50 and a lower, face dressing unit 51. Framework 25 further includes on the front side thereof a downwardly facing, frame-extension 55 having a laterally extending dovetailed groove 56 in the bottom face thereof, for the laterally-slidable, hanging support therein of the reciprocating 30 drill receiving and holding assembly C of machine 20, to be fully discussed further below.

Wheel-dressing units 50 and 51, each consist of a hand-crank 60 on a very steadily held, rotatable, threaded shaft 61 extending parallel to an adjacent surface of grinding wheel 45. A diamond-holding block 62 is 35 slidably held against rotation in each unit 50 and 51 and is threadedly engaged with shaft 61. A diamond 63 projects outwardly from each block 62 in the direction of grinding wheel 45. In the present embodiment, the hollow cylindrical grinding wheel 45 includes two faces involved in the grinding operation, namely, an annular, front face 65 in a plane perpendicular to shaft 41 and an annular, outer, front corner face 66 extending radially outwardly and rearwardly from front face 65 at an angle in the order of 45°, in accordance with the angle of upper angular dressing unit 50. By rotation of each of the two hand cranks 60, diamonds 63 in each of units 50 and 51, are caused to move adjacent and relative to grinding wheel faces 66 and 65 respectively.

60 Thus, it will be seen that when grinding wheel redressing is desired, a slight measured rotation of hand crank 61 will cause framework 25 to slide rearward in the order of thousandths of an inch, whereat the framework is locked in position. Wheel dressing units 50 and 51 are 65 then hand operated by cranks 60, passing diamonds 63 along faces 66 and 65 respectively at this new rearward position, preparing a new grinding face, properly disposed

relative to the drill-receiving and holding assembly C which were moved rearward simultaneously with the framework 25.

Disposed above, and to the right side of grinding-wheel motor 35 is a reciprocal-drive motor 70 having a forwardly extending, telescopic shaft 71, including a rear, hollow, internally-slotted shaft 72 and a forward, inner-fitting, complementarily-keyed shaft 73, providing a positive rotary drive motion to an eccentric wheel 75, Fig. 2, fixed on the forward end of shaft 73. Shaft 73 is rotatably supported in a bearing 76 rearward of eccentric wheel 75.

An upwardly-bifurcated pivot-arm 77 is centrally, pivotally mounted on hexagonally headed pin 78 projecting frontward from framework 25 below bearing 76. Two upwardly extending arms 80 of pivot-arm 77 extend vertically along each side of eccentric wheel 75 and wearing-surface plates 81 slidably engaging each side of eccentric wheel 75. Pivot-arm 77 further includes a single, downwardly-extending lever-arm 82, pivotally connected at its lower end to a reciprocating cross-arm 83, which cross-arm at its opposite end, is linked to the reciprocating, chuck carriage 85.

Carriage 85 is the general frame portion of the drill receiving and holding assembly C of machine 20, mentioned above. For assembling purposes discussed further below, carriage 85 is formed of two segments, upper segment 91 and lower segment 92, however, for clarity, carriage 85 may be considered and will be generally described as a single element. Carriage 85 includes, first, an upper-face 86 having a laterally-extending, dovetailed, raised portion 87, second, a rear-face 88 and, third, forwardly-extending, side-walls 89 and 90. Cross-arm 83 is linked to carriage 85 at an upper part of side-wall 90. Rotation of eccentric wheel 75 will be seen to cyclically pivot pivot-arm 77 causing reciprocating-arm 83 to reciprocate, slidably reciprocating carriage 85 and all its associated parts, discussed further herebelow.

Generally centered in the rear-face 88 of carriage 85, and between segments 91 and 92, is a circular hole 100, Fig. 5, extending therethrough in part and extending sufficiently rearward into face 88 throughout the balance of the extent of hole 100 for the reception therein of the innermost, shank-portion 101 of the machine-chuck 105. Shank-portion 101 is fixedly held in hole 100 by the clamping engagement between segments 91 and 92, held together by bolts 106, Fig. 4.

Chuck 105 is shown in Fig. 5, an upper portion in full and a lower portion generally in section, and is also shown complete in an exploded view in Fig. 6. Chuck 105 includes means for receiving a drill 110, the present embodiment of machine 20 being adapted for pointing or resharpening a twist drill as more fully disclosed and shown in my U. S. Patent 2,675,841. Drill 110 is formed of a cylindrical body having a generally plain shank end and a helical flute 111 in the bit end. The end face of the drill bit end has a flat surface 112 disposed acutely to the drill axis. At one side of the end face, spaced from the end of flute 111, is a wedge-like projecting knife formation 113 with an inner inclined plane 114. Since the drill end face structure determines the necessary angular disposition of chuck 105 relative to grinding wheel 45, it will be noted that to obtain a proper end profile with a horizontal disposition of the intersection of faces 112 and 114, resulting from horizontal reciprocation of carriage 85, the axis of hole 100, and thus the axis of chuck 105, extends, in the present embodiment, upwardly and outwardly at an angle of 17° from the horizontal, Fig. 5, and at an angle of 7° to a vertical fore and aft plane through the axis of grinding wheel 45, Fig. 3.

Chuck 105 includes the fourteen parts shown in the exploded view, Fig. 6, substantially all of which can be seen assembled in Fig. 5. Shank-portion 101 of chuck 105 is the smaller-diameter, inner-end-portion of slotted, radially-outer-sleeve 120. Sleeve 120 extends, Fig. 5,

the entire axial length of chuck 105, although in the sectional view the axially outer extent is hidden by the axially-extending legs 121 of the dual-armed cam-follower 122, slidably inserted within two diametrically-opposed, axial slots 123 in the larger-diameter body-portion 124 of sleeve 120.

The entire axial length of shank-portion 101 of sleeve 120 is disposed in hole 100 and, thus, the inner end of the larger-diameter body-portion 124 abuts an inner, flat surface 128 of rear-wall 88. Surface 128 is in a plane perpendicular to the chuck axis and extends radially outward beyond the periphery of the body-portion 124. A compression-spring 130 is disposed about the periphery of body-portion 124, axially inwardly abutting the radially outer portion of surface 128.

Spring 130, under compression, abuts at the axially outer end thereof, the axially inner edges of radially-outwardly-extending follower-arms 131 of cam-follower 122, constantly urging cam-follower 122 axially outwardly. The axially outward urging of cam-follower 122 causes arms 131 to follow the annularly-disposed, circumferentially-spaced, series of ramp-like cams 134 projecting axially inward on the axially inner side of an annular cam-ring 135, which ring 135 is rotatably mounted about body-portion 124.

An internally-threaded, annular, retainer-ring 138 is screwed onto an externally-threaded end 139 of outer-sleeve 120, and with axially-outer-faces of ring 138 and sleeve 120 flush, ring 138 is locked to sleeve 120 by a set-screw 140 extending radially through ring 138.

Thus, retainer-ring 138 prevents the outward movement of cam-ring 135 which is urged by spring 130 pushing against follower 122 and cam-ring 135, cam-ring 135 remaining axially stationary in abutting relation to retainer-ring 138. Cam-follower 122 is restrained against rotation by its disposition in slots 123 in the fixed outer-sleeve 120, but being axially slidably in slots 123, follower 122 cyclically reciprocates in conformance with the cams 134, against which it is urged, when cam-ring 135 is caused to rotate. One complete reciprocation slowly inward, then instantaneously outward, occurs in the sharpening of each drill, as discussed further below.

Cam-follower 122 further includes an axially-forward, small-diameter, internally-threaded ring 142, from diametrically opposite sides of which arms 121 extend axially inwardly. Ring 142 is slidably disposed within body-portion 124 of outer-sleeve 120, there being a relatively large diameter bore therefor at the outer extent of outer-sleeve 120, see Fig. 6.

An inner-sleeve 144 is slidably disposed within sleeve 120. Inner-sleeve 144, having an externally-threaded, axially-outer-end 145, is threadedly affixed to ring 142 of follower 122.

Inner-sleeve 144 further includes a drill-flute-engaging 55 positioning-pin 146 at a very closely calculated axial position therealong. Pin 146 is press fit into a radial hole 147 in sleeve 144, the outer end of pin 146 being flush with the outer periphery of sleeve 144 so as not to interfere with the slidability of inner-sleeve 144 in outer-sleeve 120. Pin 146 projects radially inward into the center, axial, drill-receiving hole 148 in sleeve 144, engaging the full width of flute 111 of drill 110. When the drill is inserted through sleeve 144 of chuck 105, the projecting portion of pin 146 prevents any drill movement other than a threading in accordance with the pitch of flute 111. The critical position of pin 146 predetermines the resultant relation between the drill projecting-knife-formation 113 and the adjacent flute 111, on a resharpened drill.

Considering further the cam-ring 135, the radially-outer-periphery includes a relatively larger diameter, toothed-annulus 150 and axially-outward thereof of a relatively smaller diameter, smooth periphery, shoulder 151. A crank 153, having an upper annular ring 154, is slidably mounted for rotation, or pivoting, on shoulder 151.

Ring 154, having an axial thickness only slightly less than the axial length of shoulder 151, is loosely held axially between annulus 150 and retainer-ring 138. Extending downward from ring 154 is a crank-arm 155, having an internally-threaded pawl-retaining-bolt hole 158, further therebelow a pull-rod-socket-pin hole 159, and to the side thereof a spring-receiving hole 160.

A pawl-retaining bolt 165 extends through and has pivotally mounted thereon a driver-pawl 166, and further extends and is threadedly affixed in hole 158 in crank-arm 155. A pull-rod-socket receiving pin 168 has a threaded end 169 extending through hole 159, thence through a spring-holder clip 170. Nut 171 is screwed tightly onto end 169 affixing pin 168 and clip 170 to crank-arm 155. Tension-spring 173 is hooked at its lower end to clip 170 and at its upper end to a rear lug 174 on pawl 166, pivotally urging the diametrically-opposite tongue 175 of pawl 166 upward into constant abutment and engagement with toothed-annulus 150 of cam-ring 135.

Referring now to Fig. 2, a stationary-pawl 180 is pivotally mounted on a fixed pin 181 projecting outward from rear-face 88 of carriage 85. Pawl 180 is disposed relative to toothed-annulus 150 such that a tension-spring 183, hooked to carriage 85 and the rear-lug 184 of pawl 180, constantly urges the diametrically-opposed tongue 185 of pawl 180 against the toothed-annulus 150 restraining counter-clockwise rotation of cam-ring 135.

An adjustable-length rod 188, having a socket-head 190 pivotally affixed to pin 168, on arm 155, extends laterally from pin 168 through a hole 192 in a fixed bar 194. Bar 194 is mounted on the side of front, frame-extension 55, extending downwardly therefrom, and remaining fixed and stationary during reciprocation of carriage 85, chuck 105, and rod 188. Rod 188 has an enlarged head 195 incapable of passing through hole 192. A tension-spring 196 is attached to crank-arm 155 at hole 160 and to a flange 198 extending outward from rear-face 88 of carriage 85. Spring 196 constantly urges crank-arm 155 to turn counter-clockwise.

A boss 200 extends outward from rear-face 88 and has threaded therethrough an adjustable stop-screw 201, the butt end 202 of screw 201 being adjustably disposed in the path toward which crank-arm 155 is urged by spring 196.

From the above, it will be seen that the lateral reciprocation of carriage 85 and chuck 105 by cross-arm 83, will cause rod 188 to reciprocate in hole 192. To obtain the desired minute advancement of drill 110 toward grinding-wheel 45 once each reciprocal cycle, rod 188 is adjusted to such a shortened length that head 195 contacts bar 194 prior to the completion of the motion of carriage 85 toward the right. Thus, during the balance of the carriage right motion, spring 196 is forced to spread; crank-arm 155 is caused to pivot clockwise; pawl 166, engaged with toothed-annulus 150, rotates cam-ring 135; and cam-follower 122 is forced inward by relative motion of cams 134. When the carriage again moves left, spring 196 pulls crank-arm 155 back against stop-screw 201; pawl 166 slides back along toothed-annulus 150, which is held stationary by pawl 180. The amount of inward movement of follower 122 each cycle, or the number of cycles required for follower 122 to progress to the innermost position, will be dependent upon the amount of rotation of cam-ring 135 each cycle, or the number of teeth advanced each cycle. This amount may be altered by a machine operator by varying the length of rod 188.

Referring to Figs. 2, 3, 4 and 5, a drill-holder 205, is shown removably clamped in an abutting relation to chuck 105 by a clamping-jig 206 which is slidably mounted outwardly from carriage 85 on two shafts 208. Shafts 208 are press fit into holes in carriage side-walls 89, and extend outwardly therefrom in a direction paral-

lel to the axial direction of chuck 105. Jig 206 includes two bearing-sleeves 210 which are slidably mounted on the shafts 208. Each shaft 208 has an enlarged outer-head, preferably a washer 212 and bolt 214 affixed to the outer end of the shafts. Compression springs 216 are disposed on shafts 208 between each bearing sleeve 210 and the respective side-wall 89 and also between each bearing-sleeve 210 and the respective washer 212, to maintain the disposition of jig 206 when tool 205 is removed therefrom.

Jig 206 has a central groove 218 extending thereacross parallel to bearings 210, for the reception of the cylindrical drill-holder 205, groove 218 having a depth slightly less than the diameter of holder 205. Holder 205, thus, projects slightly above the top surface of jig 206. A flexible locking-bar 220 is held firmly against the top surface of jig 206 at one end thereof by a press fit within a slot 222 in a raised, jig-end block 224. Bar 220 extends substantially across groove 218 and is locked downwardly, firmly holding drill-holder 205 by means of an eccentrically, pivotally mounted locking-arm 226 mounted thereabove. Locking-arm 226 is pivotally mounted on two raised bosses 228 extending upwardly from jig 206.

Drill-holder 205, Figs. 3 and 5, includes a cylindrical hollow body 230, an inner end, cylindrical, tightening ring 232, a long, knurled-head, drill-depth-adjusting, bolt 234, and an adjusting-bolt-locking set-screw 236. Adjusting-bolt 234 is threadedly adjustably disposed in the outer end of hole 238, which hole extends axially and centrally through body 230. Body 230 is internally threaded adjacent the outer extent of hole 238 for the threaded reception of bolt 234. An axially-outer end-portion 240 of body 230 is partially separated from body 230 by a semi-circular radial groove 242 perpendicular to the body axis. End-portion 240 also includes a radial groove 244 parallel to the body axis extending radially outward in one direction along the base of groove 242. Grooves 242 and 244, thus, make yieldable a segment of end portion 240 adjacent both grooves, whereby set-screw 236, extending generally centrally and perpendicularly through groove 244 and threadedly engaged only below groove 244, when tightened, locks the adjusting-bolt 234 in a fixed position.

The inner end of body 230 has an end taper 248 extending from the end to a threaded cylindrical portion 250, and further includes preferably two opposed axially and radially extending slots 252, extending inward from the end preferably further than the extent of taper 248.

Ring 232 has an inside taper 254 and internal threading 256 complementary to taper 248 and threaded cylindrical portion 250, whereby tightening of ring 232 on body 230 locks drill 110 disposed therein.

As discussed above, regarding chuck 105, cam-follower 122 and inner-sleeve 144, threadedly affixed together, are the two elements of chuck 105 subject to axial motion caused by follower 122 riding against the rotating cam surfaces of ramp-like cams 134. When fully assembled and operating, drill holder 205 is held in abutment with the outer end of sleeve 144 and holder 205 and drill 110 move axially with sleeve 144. Fig. 5 shows, in full, the axially moving elements in the inward position. Several broken line portions are shown in an outward position, to clarify the axial movement.

The adjustment of rod 188 is preferably such that approximately six reciprocal cycles of carriage 85 are required to rotate cam-ring 135 one-sixth of a revolution, which is one full cycle of each of the follower arms 131 of follower 122 over respectively one of the six ramp-like cams 134. Thus, at the end of each of five reciprocations, drill 110 is moved axially inward toward grinding-wheel 45 and there held during the following reciprocation of carriage 85 and drill 110 past the grinding-wheel. At the end of the sixth such reciprocation, the further rotation of cam-ring 135 removes cams 134 from axially outward

of follower-arms 134. Spring 130, thus, moves follower 122 axially outward to its outermost starting position.

This outward movement of follower 122 simultaneously and abruptly stops the reciprocation operation of carriage 85 as will now be discussed. A double bent stop-rod 260, Fig. 2, has a laterally extending, upper-arm 262, rotatably mounted in and extending outward from each end of a hole 264 in the side-wall 90 of carriage 85. Inward of side-wall 90, rod 260 includes a short central-arm 266 extending generally downward at 90° from the inner extent of upper-arm 262. A lower-arm 268 of rod 260 extends laterally inward from the lower extent of central-arm 266 and parallel to upper-arm 262. The innermost extent of lower-arm 268 is disposed axially inward of the lower of the two follower-arms 131, Fig. 5. A coil-spring 270, Fig. 2, is disposed around upper-arm 262 immediately inward of side-wall 90, having one end held abutting carriage rear face 88 and the opposite end wrapped about central-arm 266 whereby central-arm 266 and lower arm 268 are urged to turn about rotatably mounted upper-arm 262, and lower-arm 268 is urged constantly outward against lower follower-arm 131.

Upper-arm 262, outward of side-wall 90, has a switch-arm 272 fixed thereon and extending upward therefrom. Arm 272 engages a start-stop switch 274 mounted on side-wall 90. The further-above discussed outward movement of follower 122 to its outermost starting position, following six reciprocal cycles, allows spring 270 to rotate lower-arm 268 outward, simultaneously pivoting switch-arm 272 which opens an electrical circuit 275, stopping motor 70. Motor 70 is preferably of the instantaneous braking type, stopping immediately upon opening of the electrical circuit. Switch 274, constructed for example as shown in Fig. 7, provides for manual starting by depressing a tension spring pulled lever by the operator's finger, which lever is subsequently engaged and returned to reopen the circuit by arm 272 at the end of the subsequent cycle. This restarting will ordinarily be performed after the insertion of an unsharpened drill 110.

Operation

The automatic drill-pointer 20, built in accordance with the invention, is capable of resharpening a large plurality of drills in very rapid succession, free of burning by too rapid feeding into the grinding wheel and with assurance of a proper ground angle of the drill end face relative to the drill axis and relative to the drill flutes.

Two drill-holders 205 will ordinarily be used with each machine 20, one drill-holder having a drill shank end inserted by a machine operator, at the same time that the second drill-holder with a drill therein is clamped in jig 206 of machine 20, as shown in the drawings, with the grinding operation in process.

Prior to resharpening one set of a large number of drills, all of which are already of substantially equal length, the two drill-holders to be used are adjusted, identically, so that a predetermined extent of drill 110 extends outward from the drill-holder. By using drill-holders with only certain given sets of drills, adjustment for each subsequent resharpening of the set consists of loosening set-screw 236, turning bolt 234 inward a measured distance, and retightening set-screw 236 which locks bolt 234.

When drill-holder 205 is empty, tightening ring 232 is disposed only loosely screwed onto body 230. The shank end of a drill is inserted into drill-holder 205 until bottomed against the inner end of bolt 234. Tightening-ring 232 is tightened onto body 230 by a quick tightening rotation thereof. Tightening of ring 232 causes inner taper 254 to depress taper 248 of body 230, whereby, due to the presence of grooves 252, body 230 grasps and locks drill 110 therein.

With the grinding-wheel-motor 35 ordinarily running continuously, the loaded drill-holder is mounted into

place in machine 20. The drill and drill-holder are fed through groove 218 in jig 206, and the exposed extending portion of drill is inserted in inner-sleeve 144 of chuck 105. During such insertion, drill 110 will encounter pin 146 of inner-sleeve 144. Rotation of drill and drill holder will allow the pin 146 to engage in flute 111 of drill 110 and the further insertion of drill 110 will be by a screwing of flute 111 on pin 146 until body 230 of drill-holder 205 is tightly abutting the outer face of sleeve 144 of chuck 105. In such disposition of drill 110, the drill is precisely positioned relative to grinding wheel 45 to obtain the desired end profile after any predetermined removal of drill end by grinding.

Drill-holder 205 is then locked in jig 206 by a quick downward rotation of locking-arm 226, pressing bar 220 lockingly against the drill-holder, restricting any rotation of drill-holder relative to chuck 105. The automatic resharpening operation is commenced by activation of the reciprocal-drive-motor 70, by means of switch 274, the operation thereof proceeding automatically to completion, in substantially the time required for an operator to unload a prior used drill-holder and reload for a subsequent resharpening operation.

Upon activation of reciprocal-drive-motor 70, shaft 71 rotates, driving eccentric-wheel 75. Rotation of wheel 75, Fig. 2, is clockwise, which, in the resultant reciprocating of carriage 85, causes a relatively slower motion to the left and a relatively faster return stroke. The left stroke occurs just subsequent to the previously discussed axially inward advancement of drill 110 and provides a relatively slower grinding stroke. The faster right stroke, with the drill no further advanced, provides a fast polishing stroke. By a flattened top portion on ramp-like cam 134, Fig. 5, there will be little or no advancement of the drill prior to the last reciprocal cycle and both the left and right stroke of the last reciprocal cycle provide very complete polishing of the resharpened drill.

On completion of the last reciprocal cycle, the drill is axially retracted to the starting position and rod 260 turns causing switch 274 to stop and brake reciprocal-drive-motor 70. Locking-arm 226 is then manually raised and drill-holder 205 is removed from jig 206. Grinding-wheel-motor 35 continues to drive grinding-wheel 45 and machine 20 is in condition to receive the alternate loaded drill-holder for the next resharpening operation.

Machine 20, thus, provides a novel means for automatically resharpening very rapidly, numerous twist drills, all to an exactly identical length, as is critical for use in gang drill heads. The novel machine is adapted for a wide variation of rates of feed of drills and amount of drill end material to be removed by grinding. It is readily capable of modifications in type of feed by change of cam-ring, and in type of reciprocation by change of eccentric-wheel. By proper determination of these variables, dependent on the drills to be sharpened, all drills may be automatically and very rapidly resharpened, free of any human errors in end profile, free of burning by improper feeding, smoothly polished, and all of exactly equal length.

Having completed a detailed disclosure of the preferred embodiment of my invention so that those skilled in the art may practice the same, I contemplate that variations may be made without departing from the essence of the invention or the scope of the appended claims.

I claim:

1. An automatic drill pointer comprising a grinding element, a removable drill holder having adjustable means for the predetermined depth reception of a drill shank for holding a drill, a chuck for the reception of the drill bit end projecting from said drill holder, said drill holder with said drill therein being readily mountable to a fixed position relative to said chuck, means for reciprocating said drill relative to said grinding element and mechanically controlled means for progressively advancing said drill relative to said grinding element, said advancing

means providing a controlled progressive feed whereby an improved, non-burning, resharpening is obtained.

2. An automatic drill pointer as defined in claim 1 wherein said chuck is mounted on a reciprocally mounted carriage and said removable holder is tightly held in a jig which is mounted on said carriage, said jig being slideable relative to said carriage in a direction axially of said drill.

3. An automatic drill pointer as defined in claim 2 wherein a positioning pin is disposed in said chuck for engaging the flute of said drill whereby said drill is restrained against rotation therein.

4. An automatic drill pointer as defined in claim 1 wherein said means for progressively advancing said drill include means for activating said advancing intermittently at the completion of reciprocations.

5. An automatic drill pointer as defined in claim 1 having means for intermittent progressive advancement of said drill and means for relatively slow grinding reciprocation movement immediately following said intermittent advancing and a subsequent relatively fast polishing reciprocation movement all prior to the next intermittent advancing.

6. An automatic drill pointer comprising an abrasively surfaced grinding element, a carriage reciprocally mounted relative to said grinding element, means for reciprocating said carriage, a chuck mounted on said carriage, said chuck having an outer sleeve fixedly mounted on said carriage, an inner sleeve axially slidably mounted within said outer sleeve, cam follower radial arms fixed to said inner sleeve, projecting radially outward through axial, radial slots in said outer sleeve, a cam ring rotatably mounted and axially fixed on said outer sleeve having an axially projecting, annular cam profile adjacent said radial arms, means for rotating said cam ring simultaneously with said reciprocation, spring means urging said radial arm against said cam profile, whereby said radial arms and said inner sleeve are moved axially in accordance with said cam profile, providing means for a predetermined advancement of said drill relative to said grinding element during operation.

7. An automatic drill pointer comprising an abrasively surfaced grinding element, a carriage reciprocally mounted relative to said grinding element, means for reciprocating said carriage, a chuck mounted on said carriage, said chuck having an outer sleeve fixedly mounted on said carriage, an inner sleeve axially slidably mounted within said outer sleeve, cam follower radial arms fixed to said

inner sleeve, projecting radially outward through axial, radial slots in said outer sleeve, a cam ring rotatably mounted and axially fixed on said outer sleeve having an axially projecting, annular cam profile adjacent said radial arms, means for rotating said cam ring simultaneously with said reciprocation, spring means urging said radial arms against said cam profile, whereby said radial arms and said inner sleeve are moved axially in accordance with said cam profile, said cam ring having a toothed outer periphery, a stationary pawl and a reciprocally driven pawl cooperative therewith, activated by the reciprocation of said carriage, mounted for engagement with said toothed periphery, providing means for a predetermined advancement of said drill relative to said grinding element during operation.

3. An automatic drill pointer comprising an abrasively surfaced grinding element, a carriage reciprocally mounted relative to said grinding element, means for reciprocating said carriage, a chuck mounted on said carriage, said chuck having an outer sleeve fixedly mounted on said carriage, an inner sleeve axially slidably mounted within said outer sleeve, cam follower radial arms fixed to said inner sleeve projecting radially outward through axial, radial slots in said outer sleeve, a cam ring rotatably mounted and axially fixed on said outer sleeve having an axially projecting, annular cam profile adjacent said radial arms, means for rotating said cam ring simultaneously with said reciprocation, spring means urging said radial arms against said cam profile, whereby said radial arms and said inner sleeve are moved axially in accordance with said cam profile, providing means for a predetermined advancement of said drill relative to said grinding element during operation, said chuck further including means for returning said inner sleeve and radial arms to an axially outer position after reaching an innermost position, and a stop switch activated by said return movement to deactivate said reciprocation.
